US0D1038623S

(12) **United States Design Patent** (10) **Patent No.:** **US D1,038,623 S**
(45) **Date of Patent:** **** Aug. 13, 2024**

(54) **STORAGE BOX**

(71) Applicant: **CITYLONG TECHNOLOGY DEVELOPMENT CO., LTD.**, Tianjin (CN)

(72) Inventor: **Shibing Pan**, Tianjin (CN)

(**) Term: **15 Years**

(21) Appl. No.: **29/847,503**

(22) Filed: **Jul. 25, 2022**

(30) **Foreign Application Priority Data**

Jan. 26, 2022 (CN) 202230055274.6

(51) **LOC (14) Cl.** **03-01**

(52) **U.S. Cl.**

USPC **D3/302**

(58) **Field of Classification Search**

(57) **CLAIM**

The ornamental design for a storage box, as shown and described.

DESCRIPTION

FIG. 1 is a perspective view of a storage box showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the storage box that form no part of the claimed design.

1 Claim, 8 Drawing Sheets
